UNITED STATES PATENT OFFICE.

SAMUEL PAGE, OF McALLISTERVILLE, PENNSYLVANIA.

IMPROVEMENT IN EVAPORATORS.

Specification forming part of Letters Patent No. **58,671**, dated October 9, 1866.

To all whom it may concern:

Be it known that I, SAMUEL PAGE, of McAllisterville, in the county of Juniata and State of Pennsylvania, have made a new and useful Improvement in Evaporators; and I do hereby declare the following to be a full, clear, and exact description of the nature, construction, and operation of the same, sufficient to enable one skilled in the art to which it appertains to construct and use the same, reference being had to the accompanying drawings, which are made part of this specification, and in which—

Figure 1 is a plan view of the machine. Fig. 2 is a section on the line *a b*, Fig. 1.

My improvement consists in the arrangement of the pans and their connections.

In the drawings, A is the reservoir; B, the receiving or scumming pan, which discharges its contents as required through the pipe C into the strainer D, from which the heated saccharine liquid passes to the boiling-pan E. In this pan, which is situated over the furnace F, the greater portion of the water is evaporated, as this pan occupies the hottest position.

From the boiling-pan the condensed fluid

passes to the pan G, where it is converted into sirup or molasses, and is eventually discharged at the faucet H.

I is a horizontal diaphragm or partition in the flue behind the furnace, and J is a damper so arranged as to close the flue-opening between the plate I and the bottom of the pan G when required. By means of this plate and damper the direct heat of the furnace fire may be turned on or off from the finishing-pan G, which is a matter of convenience and importance in finishing off the molasses, which is so apt to burn at this stage, especially if a little addition be made to the fire at that time.

K is a damper in the chimney, by which the activity of the fire is regulated.

Having described my invention, what I claim therein as new, and desire to secure by Letters Patent, is—

The arrangement of the pans A E G, with the connecting-pipe C, strainer B, and the furnace-flues, substantially as described and represented.

SAMUEL PAGE.
